ATTORNEYS

UNITED STATES PATENT OFFICE.

HARRISON M. SEAGERS, OF GENEVA, NEW YORK, ASSIGNOR TO HULSE MANUFACTURING COMPANY, OF GENEVA, NEW YORK, A CORPORATION OF NEW YORK.

EMBOSSING PRESS.

Application filed December 23, 1924. Serial No. 757,669.

To all whom it may concern:

Be it known that I, HARRISON M. SEAGERS, a citizen of the United States, and resident of Geneva, in the county of Ontario 5 and State of New York, have invented certain new and useful Improvements in Embossing Presses (Case No. 8), of which the following is a specification.

This invention relates to improvements in 10 embossing presses and has for its principal objects to provide an efficient and compact hand-operated press of simple and inexpensive construction adapted to develop a very heavy pressure with slight effort on the part 15 of the operator; to provide a convertible press readily adaptable for either hot or cold embossing; to provide a press readily adapted for use with dies supported face upward over the lower press head or face down 20 under the upper press head; to provide improved means for raising and lowering the lower press head; to provide improved means for supporting and guiding the shiftable head of the press; and to provide improved means for adjusting the 25 lower press head lifting means.

Other highly important objects of the invention are to provide an improved antifriction cam lift mechanism for presses of the 30 type disclosed in patents to Pollock, No. 1,163,740 and No. 1,497,872 and to Seagers, et al. No. 1,497,795; to provide improved means for controlling the movements of the antifriction rolling elements and thrust 35 plates and the shiftable head in presses of this type; to provide an improved raising and lowering mechanism of this type so constructed as to substantially increase the throw thereof, and consequently increase the 40 normal distance between the upper and lower press heads, without any substantial increase in the effect required to actuate the press; to simplify and improve the work supporting means; and to provide a press of 45 the type disclosed in said patents which may readily be used for cold or hot embossing.

To the foregoing and other ends, which will hereinafter appear, the invention consists in the improved constructions of devices, the arrangements of parts, and combinations of elements, set forth in the following description and particularly pointed out in the appended claims.

In the accompanying drawings, wherein 55 is illustrated one satisfactory and desirable

embodiment of the invention, and in which similar reference characters designate corresponding parts throughout the several views:

Fig. 1 is a front view of the press, partly 60 in central transverse section;

Fig. 2 is a horizontal section on the line 2—2 of Fig. 1;

Fig. 3 a vertical section on the line 3—3 of Fig. 1, the parts being in normal position;

Fig. 4 a view similar to Fig. 3 showing the carriage and lower press head at the limit of their upward movement;

Fig. 5 a vertical section on the line 5—5 70 of Fig. 1;

Fig. 6 a vertical section on the line 6—6 of Fig. 1;

Fig. 7 a perspective view of one of the retainers for the antifriction rollers;

Fig. 8 a perspective view of one of the traveling thrust or bearing plates.

Fig. 9 a fragmentary view showing the adjustable supporting means for the lower press head and its lifting mechanism in a 80 different position from that shown in Fig. 1;

Fig. 10 a plan view, and Fig. 11 a section similar to Fig. 3, of the press shown in Figs. 1 to 9, with the detachable cold embossing head member removed and the removable hot embossing head member or electrically heated die support in place on the carriage to thereby convert the press from a cold embossing press into a hot embossing press;

Fig. 12 a fragmentary perspective view of 90 the detachable cold embossing press head member;

Fig. 13 a perspective view of the detachable hot embossing press head member; and

Fig. 14 a transverse sectional view of the 95 cam shaft.

The main frame or press body is cast in one piece and is of general rectangular form, the walls of the metal casting being thick and strong. The bottom wall 1 is provided 100 with a front flange 2 and a rear flange 3 to afford a broad bearing for the press body on a work bench or other support to which the press body is rigidly held by screws or bolts 4 passing through slots 5 in said flanges. The frame or body is preferably relatively wide from side to side and relatively narrow from front to rear, as shown. Vertical side walls 6 and 7 connect the bottom wall 1 with the top wall 8 which constitutes the main 105 110 115

fixed member of a two-part non-shiftable upper press head, the lower face 9 of said wall 8 being flat and disposed in a horizontal plane. The inner faces of the side walls are 5 parallel with each other and lie in vertical planes. The top face of the bottom wall 1 has a raised flat horizontal central portion 10 connected by downwardly and outwardly inclined portions 11 with two lower flat horizontal end portions 12.

The lower or vertically shiftable press head member 13, together with the parts carried thereby, is supported on a pair of independently adjustable leveling and supporting blocks 14 through the medium of the antifriction cam mechanism by which said head member 13 is shifted, as more fully hereinafter set forth. Each of the blocks 14 has a flat top face while its bottom face is 20 parallel with the top face from the outer end of the block to a point about midway the ends of the block and then extends upwardly and inwardly in an inclined plane to the inner end of the block. The junction of the 25 two inclined bottom face portions of the block forms a fulcrum portion 15 extending fore and aft of the press which engages the adjacent inclined face portion 11 of the bottom wall 1 of the frame and is adapted to 30 rock thereon and slide up and down face 11. A split ovate leaf spring 16 is confined under compression between the reduced inner ends of blocks 14 and normally urges the blocks toward the side walls 6 and 7 of the 35 press body against the rounded inner ends of adjusting screws 17 which pass through threaded holes in the side walls of the press body.

Blocks 14 are preferably formed of cast iron and constitute adjustable and rockable supporting wedges seated within the main frame of the press which is also preferably formed of cast iron. Head member 13 is a flat, horizontally disposed oblong block preferably formed of hard steel. The ends of member 13 slidably engage and are guided by the vertical inner faces of walls 6 and 7 and its front and rear edges are engaged and guided in all positions of the shiftable 50 head member by the slightly inwardly turned upper edges of sheet steel face plates 18 which are detachably held to the press body by screws 19 and close the lower portion of the open front and rear sides of the 55 rectangular body or main frame.

The head member 13 is shifted up and down by imparting rotary motion to a member 22 and horizontal reciprocating motion to a pair of thrust members 20 between which 60 member 22 rotates. These three members are preferably formed as shown and geared together, and member 22 preferably has a vertical movement in a plane through its axis, but the construction of the lifting mechanism may be widely varied. In the

present application claims are made to generic features of the invention as well as claims to the particular embodiment thereof shown in the drawings. Certain modified constructions of presses will be shown and 70 particularly claimed in other applications.

The member 22 shown comprises a steel cam shaft having two parallel flat faces 22^a and 22^b tangential to two reduced cylindrical bearing portions 22^c and 22^d, two cam faces 75 22^e and 22^f eccentric to the bearing portions and connecting the flat faces, and a projecting end portion 22^g adapted to fit in the socket 23 of a metallic hand lever 24. Face 22^e rises slightly from its junction with face 22^f to its junction with face 22^a while face 22^f rises slightly from its junction with face 22^a to its junction with face 22^b. For convenience in manufacture part 22^g is formed at the same time and the same shape as the 80 main working section of the cam shaft, and lever socket 23 shaped to fit over part 22^g to which it may be locked by a set screw as shown in Fig. 6. The parts of the lifting mechanism are normally in the positions 85 shown in Figs. 1, 2, 3, 5 and 6, being arrested in this position by engagement of a stop lug 25 on lever 24 with end wall or stop abutment 26 at one end of a segmental recess 27 formed in a boss 28 on the outer face of wall 90 7 of the press body. Stop 25 moves in this recess when lever 24 is actuated. Bearing portions 22^c and 22^d correspond in diameter 95 with the width of vertically elongated slots, ways, or bearings 29 and 30 in walls 6 and 7 and slide up and down and rotate therein. The flat faces of the cam shaft are spaced 100 apart a distance equal to the diameter of the bearing portions so that the shaft may be passed through slot 30 in assembling the 105 press.

The thrust members 20 are identical in form and interchangeable, each comprising a relatively thick steel plate oblong in plan, one face being flat throughout and the other face being flat and parallel with the first mentioned face from the outer end to a line adjacent and parallel with the inner end of the plate and then inclining toward the first mentioned face and the inner end of the plate. The inner portions of the plates are thus reduced in thickness by cutting away one face of each plate near one end, and in the construction shown said face is cut away to form an inclined plane surface. The plates 20 are arranged normally with the inclined faces of the reduced portions thereof engaging the flat faces of the cam shaft so that the shaft is supported by the lower plate and the upper plate is supported by the shaft with the flat faces of the shaft extending downwardly and rearwardly in planes parallel with the inclined faces of the reduced inner portions of the thrust plates.

Antifriction rolling elements are arranged over the upper thrust plate and below the lower thrust plate and preferably, as shown, steel non-traveling bearing plates 21 are interposed between the lower set of rolling elements and the wedge blocks and between the upper set of rolling elements and the bottom face of head member 13. Plates 21 are flat and relatively thin and are oblong in plan view. As shown the rolling elements comprise two sets of steel rollers 31 extending transversely of the press, the ends of the rollers in each set being confined in longitudinal slots 32 in a pair of sheet steel retainer bars 33. Bars 33 are disposed in vertical planes and extend fore and aft of the press opposite and close to the side edges of plates 20 and 21.

The upper pair of retainer bars extend over the cam shaft and the lower pair of bars extend under said shaft, said bars being reversible and interchangeable and having one longitudinal edge thereof cut away near one end and the reduced end portion thus formed bent laterally at a right angle to the main body portion to form a lug, hook or projection 34 engaging behind the outer edge of the adjacent thrust plate 20 but free from the adjacent bearing plate 21. The outer edges of plates 20 are preferably cut away to form recesses 35 in which the projections 34 seat when the parts are in normal position.

A positive mechanical driving connection is preferably provided between each traveling member 20 and the rotary and vertically sliding member 22 of the head shifting mechanism. As shown these connections are toothed gear connections and comprise two rows of short teeth 36 on each thrust plate 20 extending fore and aft of the press meshing with two circumferential rows of recesses or tooth sockets 37 formed in the main working portion of the cam shaft. Teeth 36 are provided on both the inclined and horizontal portions of the adjacent faces of the two plates 20 and sockets 37 are provided in both the flat and eccentric faces of the shaft 22, the rows of teeth and sockets being of sufficient length to maintain the driving connections throughout the range of movement of the parts. The positive drive thus provided insures prompt and uniform movement of plates 20, provides for positively restoring the roller bearings to the same point after each press operation, and assists in preventing accidental displacement of the traveling elements of the lifting mechanism.

It will be observed that the head member 13 and devices thereon are supported by the lifting mechanism just described. It is highly desirable to prevent tilting of the head member 13 during shifting movements thereof or when pressure is applied to one end of

the work carriage, as such motion of the head 13 may cause derangement of the work or displacement of some part of the operating mechanism. To this end said head member is guided as above described by the side walls 6 and 7 and face plates 18 and is further supported by a combined balancing or steadyng and return mechanism which will now be described. A pair of sheet steel rectangular balancing plates 38 are hung on the reduced portions 22^c and 22^d of the shaft 22, said plates being interchangeable and provided with large circular apertures 39 through which the eccentric portion of the cam shaft may be passed. These plates are confined between the adjacent side walls of the press body and the shoulders formed at the junctions of the cylindrical bearing portions of shaft 22 with the main central eccentric portion of the shaft and thus prevent accidental endwise motion of the shaft. The plates are of such size and so located that they also prevent endwise motion of rollers 31 and cooperate with plates 20 and 21 to hold the retainer bars on the ends of the rollers. The top edges of the plates engage under the side portions of head member 13 when the parts are in normal position and the vertical front and rear edges of the plates slidably engage the face plates 18, thus forming a steady and firm support for member 13 when said member is in its normal lowermost position. To further steady and guide the parts, insure prompt and easy return of the parts to normal position, and to limit the extent of upward motion of member 13, a pair of steel stop bars 40 are provided. These bars 40 extend fore and aft of the press body along the inner faces of walls 6 and 7 and are constantly held pressed up against the lower flat face 9 of the top wall or fixed head member 8 by coil springs 41. Each block is supported near its front and rear ends at each side of the vertical plane of the cam shaft by two of the springs 41, the upper ends of the springs being seated in sockets 42 in the bar and the lower ends of the springs being seated in sockets 43 in the member 13. Lateral motion of the springs and bars is prevented by guide pins or posts 44 seated loosely in sockets 43 and passing up through the coils of the springs part way into the sockets 42. Springs 41 are normally under compression and tend to constantly press member 13 downward, the pressure being exerted adjacent each of the four corners of head member 13. The parts are kept under constant and even pressure in such manner as to insure easy and prompt action and prevent accidental displacement thereof.

The press is preferably provided with a fore and aft shifttable work support or traveling carriage 45, which in the construction shown is several times as long as the dis-

tance between the front and rear edges of head members 8 and 13 and is detachably and slidably held to member 13 by a guiding and retaining rod 46 to slide back and forth on the top face of member 13 in a horizontal plane. The carriage comprises a long flat sheet steel plate having upstanding vertical side flanges 45^a disposed in planes just inside the stop bars 40, and also having depending end flanges 45^b and 45^c through apertures in which rod 46 passes. Rod 46 passes through notches 18^a in plates 18 and through a horizontal central bore or cylindrical slideway 47 extending fore and aft through member 13 and has a forward head 46^b abutting against the front face of flange 45^b and is provided with a transverse bore 46^b near its other end so disposed that a removable fastening or cotter pin 48 passed therethrough abuts against the rear face of flange 45^c. The end flanges are stiffened where the rod passes therethrough by stamping out parts of the bed of the carriage and turning them down to form short depending flanges 49 close to and parallel with the adjacent end flanges. These flanges 49 are also adapted to act as stops and engage the front and rear edges of the member 13 above the top edges of the face plates to limit fore and aft movements of the carriage and keep any part thereof from being jammed against the face plates 18. A handle 50 is affixed to flange 45^b, said handle preferably comprising a metal rod bent to U-shape and having reduced ends passing through the flange and headed down against the rear face of the flange as shown at 50^a. The carriage has a continuous plane surface adapted to support long pieces of work or both long pieces of work and long dies or die forms, or a series of short pieces of work or long series of both short work pieces and short dies or die forms, and by shifting the carriage longitudinally between successive squeezing operations of the press it will be evident that successive areas of work may be presented between the head members, which are relatively short from front to rear as above described.

To adapt the press for either hot or cold embossing with the die or die form supported on either the stationary upper head or the shiftable lower head, two flat detachable and interchangeable head members are provided, the member 51 comprising a solid steel block or cold embossing head member and the member 52 comprising a hot embossing head member consisting of a flat metal block having an electric heating element 53 set in the obverse face thereof in the well known manner and covered by a metal face plate 52^a, the reverse face of said block 52 having a covering 52^b of heat insulating material thereon.

The combined thickness of parts 52, 52^a and 52^b of the hot head member is equal to the thickness of the cold head member, and head member 51 is provided with a conoidal socket 54 in both the fore and aft side edges thereof near its reverse face 70 midway between the front and rear edges of the member, while head member 52 is provided with a similarly located pair of conoidal sockets 55. Either of the head members 51—52 may be firmly secured to the fixed head member 8 with the reverse face thereof pressed firmly against the bottom face 9 of said member 8 by screwing the conoidal ends of screws 56 into the sockets in the side edges of the detachable member. The screws 56 are threaded in apertures 57 in the side walls at such a level with regard to the sockets that they will cam the detachable head member firmly against member 8 (see Fig. 1) so that 80 the detachable member may be held firmly in place by only two screws. Members 51 and 52 are of such width that their side edges terminate inside the flanges 45^a of the carriage which may move up and down 90 between the blocks 40 and the sides of either head member that may be held to member 8. The nonthreaded inner portions of the shanks of screws 56 pass loosely through apertures 58 in stop bars 40 and are located 95 above the limit of upward movement of the upper edges of flanges 45^a and the carriage 45.

Cold embossing.

In Figs. 1 to 4 the cold embossing head member 51 is shown attached to fixed head member 8 to adapt the press for use in embossing by the cold process. In some classes of work it is preferred to work with dies supported in inverted position above the material to be acted upon. This method of embossing may be performed by placing the material on the carriage and (1) placing the inverted die or dies on the material and forcing both dies and material up toward member 51, or (2) cementing the inverted die or dies to the under face of head member 51 and forcing the material up toward the die and member 51, or (3) where very thick dies or material are used, by removing member 51 and either cementing the die to the bottom face 9 of head member 8 or placing the die face down on the work on the carriage. It is usually preferable, however, to work with dies supported face up on the lower head with the material to be embossed laid over the dies. This is especially true when using the press to make embossed display cards or the like of the character referred to in the patents mentioned above. For this class of work the die or die form may be (1) simply placed face up on the carriage 45 and the material placed on the die or (2) the die or die form may be ce- 100 105 110 115 120 125 130

mented to the carriage face up or may be cemented or otherwise secured to or in a chase or holder placed on the carriage. The carriage is well adapted for use with a chase or set up card of the character disclosed in the application of Lublitz and Trokie, Serial No. 747,806, filed November 4, 1924.

Hot embossing.

To adapt the press for embossing by the hot process, head member 51 is removed and the electrically heated head member 52 is (1) attached to head member 8 by the screws 56 or (2) placed on the carriage as shown in Figs. 10 and 11. Studs or short projections 59 are preferably pressed inward from the body of flanges 45^a of the carriage and are adapted to spring into sockets 55 in member 52 to assist in detachably holding the member to the carriage. When member 52 is held against member 8 the press is adapted for use with inverted dies which may be cemented to face 52^a of the heated head or may be placed on the material on the carriage and shifted up against the heated head. When the member 52 is attached to the carriage, as shown in Figs. 10 and 11, the dies or die form may be simply placed on or may be cemented to the face plate 52^a of the member with the faces of the dies uppermost and the material placed over the dies and squeezed against face 9 of head member 8. As it is, as above set forth, usually preferable to employ dies arranged face up and as it is frequently desired to employ long dies or forms, member 52 is preferably made several times as long as the distance between the front and rear faces of the press body, as shown, so as to cover all or substantially all of the flat surface of the carriage that is shiftable forwardly of the two head members 8 and 13. A suitable flexible electric conductor cable or cord 60 is provided for connecting heater 53 with a source of current, the cable being provided with attachment plugs of ordinary form and being of sufficient length to permit free movement of the heated head with the carriage.

It will be observed from the foregoing description that a simple and powerful press of compact construction is provided capable of use in a wide variety of ways for embossing materials, the press shown with a face area of about nine inches by four inches for heads 8 and 13 being capable of developing a pressure of approximately eight tons with application of comparatively slight effort to the hand lever 24. It will be evident that while the press is particularly suitable for use as an embossing press it is not limited to such use and, while it is highly advantageous especially in embossing work to employ the long

sliding carriage, the carriage may be removed as well as the detachable head members, and that head member 13 may be employed to directly instead of indirectly support the work, or the work and dies, or the heated head member, if desired.

It will be observed that when either member 51 or member 52 is attached to member 8 a fixed head is provided comprising two detachably connected sections, and that when members 52 is attached to the carriage a vertically shiftable head is provided comprising two sections one of which is detachable and is also horizontally shiftable relatively to the other and of substantially greater length from front to rear of the press.

By adjusting blocks 14 uniformly toward or from each other the member 13 and carriage and the entire lifting mechanism may be bodily elevated to vary the normal distance between the squeezing heads. Shim plates may be interposed between member 13 and the adjacent bearing plate or between blocks 14 and the adjacent bearing plate, or at both these points, if desired to effect very substantial change in the normal level of member 13. As the several plates and anti-friction rollers between member 13 and blocks 14 are relatively long and may vary in thickness slightly from end to end, the blocks 14 may be adjusted as shown in Fig. 9 or in the opposite direction to compensate for such variation and maintain member 13 perfectly level. By constructing the blocks 14 as above described it will be noted that when adjusted as above set forth they tilt so that the top faces of both blocks lie in the same plane (see Fig. 9), which is a highly desirable and novel feature of the adjustable supporting means.

With the parts as shown in Fig. 3, forward rocking of the hand lever for about one-fourth of its throw will turn the cam shaft until the flat faces inclined slightly forward and downward and the lower parts of the eccentric faces begin to roll on the horizontal parts of the toothed faces of the horizontal moving thrust plates, thus causing a quick substantial upward sliding movement of the cam shaft in its bearings and a greater upward movement of the head member 13. The press is preferably adjusted so that at this point the heads are just close enough together to begin squeezing the dies against the work. The continued forward and downward movement of the lever to the position shown in Fig. 4 brings the top face of head 13 up against the stop bars 40 whereupon upward movement of head 13 is positively arrested to prevent the dies being forced too far into the work. This final lift of head 13 is relatively slight and due to the rolling of the slightly eccentric faces of the cam shaft between the plates. When

head 13 engages bars 40 stop face 25^a of lug 25 is slightly above the bottom wall 26^a of recess 27 in boss 28. If power is still exerted on lever 24 after head 13 strikes bars 40 stop face 25^a will engage wall 26^a and positively stop swinging motion of the lever before injurious strain is imposed upon the lifting mechanism. When the lever 24 is swung back to normal position plates 20 will be driven positively back to the positions shown in Fig. 3 and will positively drive the rollers 31 back to their starting position through the medium of lugs 34 on the retainers.

15 By reducing the inner ends of the thrust plates a substantial increase in throw is obtained with parts of a given proportion over presses constructed as shown in the patents above referred to without an undesirable increase in the throw of the hand lever and without increasing the effort required to operate the press. This is highly important as owing to the somewhat limited clearance in the patented presses the work or die forms 20 were sometimes deranged in sliding the same between the press heads, especially when the operator worked rapidly.

What I claim is:

1. In an embossing press, the combination 30 of a stationary head member, a vertically movable head member below the stationary head member, a traveling carriage supported on the movable head member to move vertically therewith and travel fore 35 and aft of the press relatively to said head member, said carriage being longer than the stationary head member, cam means for raising the movable head member, and spring means connected with the movable head member to transmit force thereto in a downward direction at points adjacent the front and rear edges of said member.

2. In an embossing press, the combination 45 of a stationary head member, a vertically movable head member below the stationary head member, a traveling carriage supported on the movable head member to move vertically therewith and travel fore and aft of the press relatively to said head member, said carriage being longer than the stationary head member, cam means for raising the movable head member, and compression springs interposed between the head members arranged to exert downward pressure on the movable head member near both side edges of the member at points both fore and aft of the transverse center line of the member.

3. In an embossing press, the combination 60 of a stationary head member, a vertically movable head member below the stationary head member, a traveling carriage supported on the movable head member to move vertically therewith and travel fore

and aft of the press relatively to said head member, said carriage being longer than the stationary head member, cam means for raising the movable head member, compression springs interposed between the head members arranged to exert downward pressure on the movable head member near both side edges of the member at points both fore and aft of the transverse center line of the member, and means interposed between the head members for positively limiting the extent of upward movement of the lower member. 65 70 75

4. In a press, the combination of a stationary head, a movable head member below the stationary head, means for forcing the movable head member upwardly, a pair of bars extending fore and aft of the press between the stationary head and movable head member adjacent opposite sides thereof, said movable head member being rectangular and having a socket in its upper face adjacent each corner thereof, said bars having complementary sockets in their under sides, and four coil springs having their lower end seated in the sockets in the movable head member and their upper ends seated in the sockets in the bars and yieldably forcing the bars up against the stationary head and urging the movable member to its lowermost position, said bars being engageable by the movable head member to limit the upward movement thereof. 80 85 90 95

5. In a press, the combination of a stationary head, a movable head member below the stationary head, means for forcing the movable head member upwardly, a pair of bars extending fore and aft of the press between the stationary head and movable head member adjacent opposite sides thereof, said movable head member being rectangular and having a socket in its upper face adjacent each corner thereof, said bars having complementary sockets in their under sides, four coil springs having their lower ends seated in the sockets in the movable head member and their upper ends seated in the sockets in the bars and yieldably forcing the bars up against the stationary head and urging the movable member to its lowermost position, said bars being engageable by the movable head member to limit the upward movement thereof, and four vertical posts extending through the springs from the bases of the sockets in the movable head member partly into the sockets in the bars. 100 105 110 115 120

6. In a press, the combination of a stationary head, a movable head member below the stationary head, means for forcing the movable head member upwardly, a pair of bars extending fore and aft of the press between the stationary head and movable head member adjacent opposite sides thereof, said 125

movable head member being rectangular and having a socket in its upper face adjacent each corner thereof, said bars having complementary sockets in their under sides, four coil springs having their lower ends seated in the sockets in the movable head member and their upper ends seated in the sockets in the bars and yieldably forcing the bars up against the stationary head and urging the movable member to its lowermost position, said bars being engageable by the movable head member to limit the upward movement thereof, and a long work carriage mounted on the movable head member to travel fore and aft over the same to position different areas of work under the stationary head, said stationary head being relatively short from front to rear.

7. In a press, the combination of a stationary head, a movable head member below the stationary head, means for forcing the movable head member upwardly, a pair of bars extending fore and aft of the press between the stationary head and movable head member adjacent opposite sides thereof, said movable head member being rectangular and having a socket in its upper face adjacent each corner thereof, said bars having complementary sockets in their under sides, four coil springs having their lower ends seated in the sockets in the movable head member and their upper ends seated in the sockets in the bars and yieldably forcing the bars up against the stationary head and urging the movable member to its lowermost position, said bars being engageable by the movable head member to limit the upward movement thereof, four vertical posts extending through the springs from the bases of the sockets in the movable head member partly into the sockets in the bars, and a long work carriage slidably held to and supported on the movable head member to travel horizontally under the stationary head, said stationary head being relatively short longitudinally of the carriage.

8. In a press, the combination of a stationary head, a movable head member below the stationary head, means for forcing the movable head member upwardly, a pair of bars extending fore and aft of the press between the stationary head and movable head member adjacent opposite sides thereof, said movable head member being rectangular and having a socket in its upper face adjacent each corner thereof, said bars having complementary sockets in their under sides, four coil springs having their lower ends seated in the sockets in the movable head member and their upper ends seated in the sockets in the bars and yieldably forcing the bars up against the stationary head and urging the movable member to its lowermost position, said bars being engageable by the movable head member to limit

the upward movement thereof, said stationary head comprising a fixed upper member and a removable lower member located between the bars both having flat lower pressure faces.

9. In a press, the combination of a stationary head, a movable head member below the stationary head, means for forcing the movable head member upwardly, a pair of bars extending fore and aft of the press between the stationary head and movable head member adjacent opposite sides thereof, said movable head member being rectangular and having a socket in its upper face adjacent each corner thereof, said bars having complementary sockets in their under sides, four coil springs having their lower ends seated in the sockets in the movable head member and their upper ends seated in the sockets in the bars and yieldably forcing the bars up against the stationary head and urging the movable member to its lowermost position, said bars being engageable by the movable head member to limit the upward movement thereof, four vertical posts extending through the springs from the bases of the sockets in the movable head member partly into the sockets in the bars, and a long work carriage slidably held to and supported on the movable head member to travel horizontally under the stationary head, said stationary head being relatively short longitudinally of the carriage and comprising a fixed upper head member and a removable lower head member located between the bars.

10. In a press, the combination of a stationary head, a movable head member below the stationary head, means for forcing the movable head member upwardly, a pair of bars extending fore and aft of the press between the stationary head and movable head member adjacent opposite sides thereof, said movable head member being rectangular and having a socket in its upper face adjacent each corner thereof, said bars having complementary sockets in their under sides, four coil springs having their lower ends seated in the sockets in the movable head member and their upper ends seated in the sockets in the bars and yieldably forcing the bars up against the stationary head and urging the movable member to its lowermost position, said bars being engageable by the movable head member to limit the upward movement thereof, four vertical posts extending through the springs from the bases of the sockets in the movable head member partly into the sockets in the bars, a long work carriage slidably held to and supported on the removable head member to travel horizontally under the stationary head, said stationary head being relatively short longitudinally of the carriage, and comprising a fixed upper head member and a removable

- lower head member, and means on a fixed part of the press for holding the removable head member firmly against the under face of the fixed head member between the bars.
- 5 11. In a press, the combination of a stationary head, a movable head member below the stationary head, means for forcing the movable head member upwardly, a pair of bars extending fore and aft of the press between the stationary head and movable head member adjacent opposite sides thereof, said movable head member being rectangular and having a socket in its upper face adjacent each corner thereof, said bars having 10 complementary sockets in their under sides, four coil springs having their lower ends seated in the sockets in the movable head member and their upper ends seated in the sockets in the bars and yieldably forcing the bars up against the stationary head and urging the movable member to its lowermost position, said bars being engageable by the movable head member to limit the upward movement thereof, four vertical posts extending through the springs from the bases of the sockets in the movable head member partly into the sockets in the bars, a long work carriage slidably held to and supported on the movable head member to travel horizontally under the stationary head, said stationary head being relatively short longitudinally of the carriage and comprising a fixed upper head member and a removable lower head member both having flat lower pressure faces, and means for holding the removable head member firmly against the under face of the fixed head member between the bars.
- 15 12. In a press, the combination of a stationary head, a movable head member below the stationary head, means for forcing the movable head member upwardly, a pair of bars extending fore and aft of the press between the stationary head and movable head member adjacent opposite sides thereof, said movable head member being rectangular and having a socket in its upper face adjacent each corner thereof, said bars having complementary sockets in their under sides, four coil springs having their lower ends seated in the sockets in the movable head member and their upper ends seated in the sockets in the bars and yieldably forcing the bars up against the stationary head and urging the movable member to its lowermost position, said bars being engageable by the movable head member to limit the upward movement thereof, four vertical posts extending through the springs from the bases of the sockets in the movable head member partly into the sockets in the bars, a long work carriage slidably held to and supported on the movable head member to travel horizontally under the stationary head, said stationary head being relatively short longitudinally of the carriage and comprising a fixed upper head member and a removable lower head member both having flat lower pressure faces, and means for holding the removable head member firmly against the under face of the fixed head member between the bars.
- 20 13. In a press, in combination, a two part pressure head, each part having a pressure face, and means for detachably holding the reverse face of one part in contact with the pressure face of the other part.
- 25 14. In a press, in combination, a two part pressure head, each part having a pressure face, means for detachably holding the reverse face of one part in contact with the pressure face of the other part, and means for heating the detachable head part.
- 30 15. In a press, in combination, a two part pressure head, each part having a pressure face, means for detachably holding the reverse face of one part in contact with the pressure face of the other part, and an electric heating element in the detachable head part.
- 35 16. In an embossing press, fixed and movable head members, an electrically heated head member, and means for supporting said electrically heated head member on either the fixed or movable head member.
- 40 17. In an embossing press, fixed and movable head members, means for shifting the movable head member, a supplemental head member, heating means carried by the supplemental head member, and means for supporting said supplemental member on either the fixed or movable head members.
- 45 18. In an embossing press, the combination of a fixed head member, a movable head member under the fixed head member, a long supplemental head member, electric heating means within the supplemental head member, and means for supporting the supplemental head member on the movable head member to travel horizontally under the fixed head member, said fixed head member being relatively short in the direction of travel of the supplemental head member, and means for shifting the movable head member vertically.
- 50 19. An embossing press having interchangeable head members one of which carries means for heating the same.
- 55 20. A convertible press for hot or cold embossing having a fixed head, a vertically movable head under the fixed head, a work carriage mounted on the movable head to travel horizontally relatively thereto, means for shifting the movable head with the carriage thereon vertically, said fixed head having a removable bottom section and a

flat pressure face exposed by removal of the bottom section.

21. A convertible embossing outfit comprising a non-heated head-member, a head member of the same thickness as the non-heated member and having an electric heating means therein, said two members having similarly located sockets therein, and a press having relatively shiftable head members, and retaining devices adjacent one head member thereof for engaging in the sockets of either the heated or non-heated head member to hold the same against the adjacent head of the press, said press having a horizontally sliding support on its other head also adapted to hold the heated member.

22. An embossing press having a two-part stationary head both parts of which have flat lower pressure faces, means for removably holding the lower part of the stationary head in place, a long work carriage, means for supporting the carriage to travel horizontally under the stationary head and move up and down relatively thereto, said two part head being relatively short in the direction of horizontal travel of the carriage, a flat supplemental head member having electric heating means therein and one heat insulated face, said supplemental head member being adapted to either rest on the carriage with its heat insulated face lowermost and co-operate with the pressure face of the fixed part of the stationary head to squeeze the work and die when the lower part of said head is detached or to be held to the fixed part of the stationary head with its insulated face uppermost by the holding means for the detachable part of the fixed head in position to cooperate with the carriage to squeeze the work and dies.

23. In a press, the combination of a stationary head member, a movable head member under the stationary head member, and means for shifting the movable head member vertically including a horizontally disposed thrust member and a rotatably mounted actuating member having a positive driving connection with the thrust member for shifting the same endwise, said thrust and actuating members having faces cooperating to cause an upward movement of one of the said members when the rotatable member is rotated in one direction.

24. In a press, the combination of a stationary head member, a movable head member under the stationary head member, and means for shifting the movable head member vertically including a horizontally disposed thrust member and a rotatably mounted actuating member having a positive driving connection with the thrust member for shifting the same endwise, said

thrust and actuating members having faces 65 cooperating to cause an upward movement of one of the said members when the rotatable member is rotated in one direction, said thrust member having a reduced portion engaged by the rotatable member at 70 the limit of its rotary movement in the opposite direction.

25. In a press, the combination of a stationary head, a vertically movable head under the stationary head, a rotatable actuating member below the movable head, means for rotating said actuating member, a pair of horizontally disposed thrust members arranged above and below the actuating member with the uppermost thrust 75 member disposed under the movable head, and means forming positive driving connections between the actuating and thrust members for shifting the thrust members endwise in opposite directions when the actuating member is rotated, said actuating and thrust members having cooperating faces so formed as to cause upward movement of the upper thrust member when the actuating member is rotated in one direction to thereby elevate the movable head. 80

26. In a press, the combination of a stationary head, a vertically movable head under the stationary head, a rotatable and vertically slidably actuating member, means for rotating said member, a pair of thrust members disposed horizontally above and below said actuating member with the upper thrust member located under the movable head, means supporting the lower thrust 95 member, means forming a positive driving connection between the actuating and thrust members for shifting the thrust members endwise in opposite directions when the actuating member is rotated, said actuating and thrust members having cooperating faces so formed as to cause upward movement of the actuating member and the upper thrust member when the actuating member is rotated in one direction. 100

27. In a press, the combination of a stationary head, a vertically movable head under the stationary head, a rotatable and vertically slidably actuating member, means for rotating said member, a pair of thrust members disposed horizontally above and below said actuating member with the upper thrust member located under the movable head, means supporting the lower thrust 115 member, means forming a positive driving connection between the actuating and thrust members for shifting the thrust members endwise in opposite directions when the actuating member is rotated, the adjacent faces of the thrust members being cut away adjacent the inner ends of said members, the actuating member being normally located between the reduced inner end 120

- portions of the thrust members, and said actuating member and the thrust members being so formed that continued rotation of the actuating member after the reduced portions of the thrust members have been shifted out of engagement therewith will cause continued upward movement of the actuating member and the upper thrust member.
28. A press as claimed in claim 26, in which a set of antifriction rollers are interposed between the movable head and the upper thrust member and a set of antifriction rollers are interposed between the lower thrust member and its support, the ends of the rollers being confined in retainers having projections engageable by the outer ends of the thrust members.
29. In a press, the combination of a cam, means for rotating the cam, means for supporting the cam for rotation about its axis and sliding motion in a vertical plane, a pair of horizontally disposed thrust members located above and below the cam and engaged thereby, positive driving connections between the thrust members and the cam for forcing the thrust members endwise in opposite directions when the cam is rotated, means for supporting the lower thrust member, a lower press head disposed above and shiftable upwardly by the upper thrust member when the cam is rotated in one direction, means for guiding the lower press head to move vertically, and a stationary press head above the lower press head.
30. In a press, the combination of a cam, means for rotating the cam, means for supporting the cam for rotation about its axis and sliding motion in a vertical plane, a pair of horizontally disposed thrust members located above and below the cam and engaged thereby, positive driving connections between the thrust members and the cam for forcing the thrust members endwise in opposite directions when the cam is rotated, means for supporting the lower thrust member, a lower press head disposed above and shiftable upwardly by the upper thrust member when the cam is rotated in one direction, means for guiding the lower press head to move vertically, and a stationary press head above the lower press head.
31. In a press, the combination of a cam, means for rotating the cam, means for supporting the cam for rotation about its axis and sliding motion in a vertical plane, a pair of horizontally disposed thrust members located above and below the cam and engaged thereby, positive driving connections between the thrust members and the cam for forcing the thrust members endwise in opposite directions when the cam is rotated, means for supporting the lower thrust member, a lower press head disposed above and shiftable upwardly by the upper thrust member when the cam is rotated in one direction, means for guiding the lower press head to move vertically, and a stationary press head above the lower press head, said thrust members having their adjacent faces cut away adjacent their inner ends and said cam being interposed between the reduced ends of the thrust members when the movable head is in lowered position.
32. In a press, the combination of a cam, means for rotating the cam, means for supporting the cam for rotation about its axis and sliding motion in a vertical plane, a pair of horizontally disposed thrust members located above and below the cam and engaged thereby, positive driving connections between the thrust members and the cam for forcing the thrust members endwise in opposite directions when the cam is rotated, means for supporting the lower thrust member, a lower press head disposed above and shiftable upwardly by the upper thrust member when the cam is rotated in one direction, means for guiding the lower press head to move vertically, and a stationary press head above the lower press head, said thrust members having their adjacent faces beveled at their inner ends and said cam having oppositely disposed parallel flat faces engaging the beveled face portions of the thrust members when the movable press head is in lowered position, said cam having two eccentric faces connecting its flat faces, the lowest points of the eccentric faces being disposed adjacent the inner ends of the horizontal major portions of the adjacent faces of the thrust members when the flat faces of the cam are engaged with the beveled face portions of the thrust members.
33. In an embossing press, the combination of a fixed press head, a vertically movable press head under the fixed head, a horizontal cam shaft having an eccentric portion extending transversely of the press under the movable head and having cylindrical bearing portions, a work carriage, means supporting the carriage on the movable head to travel fore and aft of the press between the heads, means cooperating with the cylindrical bearing portions of the cam shaft to support and guide the shaft for rotation about its axis and vertical sliding movement, horizontally disposed thrust plates located above and below the eccentric portion of the cam and engaged thereby, said plates being movable fore and aft of the press by the shaft, supporting means

below the lower thrust plate, antifriction bearing devices interposed between the supporting means and the lower plate, antifriction bearing devices interposed between the 5 upper plate and the movable press head, a pair of supporting and balancing plates hung on the cylindrical bearing portions of the cam shaft and having horizontal upper edges engaging under and supporting the 10 movable press head when said head is in lowered position, and means holding said plates against turning movement about the cam shaft.

34. In an embossing press, the combination of a fixed press head, a vertically movable press head under the fixed head, a horizontal cam shaft having an eccentric portion extending transversely of the press under the movable head and having cylindrical bearing portions, a work carriage, means supporting the carriage on the movable head to travel fore and aft of the press between the heads, means cooperating with the cylindrical bearing portions of the cam shaft to support and guide the shaft for rotation about its axis and vertical sliding movement, horizontally disposed thrust plates located above and below the eccentric portion of the cam and engaged thereby, said plates being movable in opposite directions fore and aft of the press by the shaft, supporting means below the lower thrust plate, antifriction bearing devices interposed between the supporting means and the lower plate, antifriction bearing devices interposed between the upper plate and the movable press head, a pair of supporting and balancing plates hung on the cylindrical bearing portions of the cam shaft and having horizontal upper edges engaging under and supporting the movable press head when said head is in lowered position, means holding said plates against turning movement about the cam shaft, and spring means constantly exerting force in downward direction on the movable head at points both fore and aft of the cam shaft.

35. In an embossing press, the combination of a fixed press head, a vertically movable press head under the fixed head, a horizontal cam shaft having an eccentric portion extending transversely of the press under the movable head and having cylindrical bearing portions, a work carriage, means supporting the carriage on the movable head to travel fore and aft of the press between the heads, means cooperating with the cylindrical bearing portions of the cam shaft to support and guide the shaft for rotation about its axis and vertical sliding movement, horizontally disposed thrust plates located above and below the eccentric portion of the cam and engaged thereby, said plates being movable fore and aft of the press by the shaft, supporting means below the lower

thrust plate, antifriction bearing devices interposed between the supporting means and the lower plate, antifriction bearing devices interposed between the upper plate and the movable press head, a pair of supporting and balancing plates hung on the cylindrical bearing portions of the cam shaft and having horizontal upper edges engaging under and supporting the movable press head when said head is in lowered position, means holding said plates against turning movement about the cam shaft, a pair of coiled compression springs interposed between the press heads and connected with the lower head near opposite sides thereof forward of the vertical plane of the cam shaft, and a second pair of coiled compression springs interposed between the press heads and connected with the lower head near opposite sides thereof in rear of the vertical plane of the cam shaft.

36. In an embossing press, the combination of a fixed press head, a vertically movable press head under the fixed head, a horizontal cam shaft having an eccentric portion extending transversely of the press under the movable head and having cylindrical bearing portions, a work carriage, means supporting the carriage on the movable head to travel fore and aft of the press between the heads, means cooperating with the cylindrical bearing portions of the cam shaft to support and guide the shaft for rotation about its axis and vertical sliding movement, horizontally disposed thrust plates located above and below the eccentric portion of the cam and engaged thereby, said plates being movable fore and aft of the press by the shaft, supporting means below the lower thrust plate, antifriction bearing devices interposed between the supporting means and the lower plate, antifriction bearing devices interposed between the upper plate and the movable press head, a pair of supporting and balancing plates hung on the cylindrical bearing portions of the cam shaft and having horizontal upper edges engaging under and supporting the movable press head when said head is in lowered position, means holding said plates against turning movement about the cam shaft, a pair of coiled compression springs interposed between the press heads and connected with the lower head near opposite sides thereof forward of the vertical plane of the cam shaft, and a second pair of coiled compression springs interposed between the press heads and connected with the lower head near opposite sides thereof in rear of the vertical plane of the cam shaft, a pair of stop bars extending fore and aft under the fixed press head at opposite ends of the carriage and engageable by the lower press head, said bars and lower head having sockets in which the upper and lower ends 130

of said coiled springs are seated, and guide posts seated in the sockets in the lower head and extending upwardly through the springs partly into the sockets in the bars.

37. In an embossing press, the combination of a fixed press head, a vertically movable press head under the fixed head, a horizontal cam shaft having an eccentric portion extending transversely of the press under the movable head and having cylindrical bearing portions, a work carriage, means supporting the carriage on the movable head to travel fore and aft of the press between the heads, means cooperating with the cylindrical bearing portions of the cam shaft to support and guide the shaft for rotation about its axis and vertical sliding movement, horizontally disposed thrust plates located above and below the eccentric portion of the cam and engaged thereby, said plates being movable fore and aft of the press by the shaft, supporting means below the lower thrust plate, antifriction bearing devices interposed between the supporting means and the lower plate, antifriction bearing devices interposed between the upper plate and the movable press head, a pair of supporting and balancing plates hung on the cylindrical bearing portions of the cam shaft and having horizontal upper edges engaging under and supporting the movable press head when said head is in lowered position, means holding said plates against turning movement about the cam shaft, spring means constantly exerting force in downward direction on the movable press head at points both fore and aft of the cam shaft, said balancing plates being confined between the supporting and guiding means for the cam shaft and the adjacent ends of the eccentric portion of the cam shaft and the antifriction bearing devices being confined between the inner faces of the balancing plates.

38. In a press, the combination of a press body having top, bottom and fore and aft side walls, the top wall having a flat under face and the bottom wall having two inclined upper face portions extending downwardly and outwardly toward opposite sides of the body, a pair of tilttable wedge blocks having fulcrum portions slidably engaging the inclined face portions of the bottom wall and supporting the blocks to tilt about axes extending fore and aft of the press body, a pair of adjusting screws threaded through the side walls of the press body, a compression spring interposed between the inner ends of the wedge blocks and urging the blocks outwardly against the inner ends of the screws, a vertically movable head located under the top wall of the press body, and supporting and lifting mechanism for the movable head mounted on the wedge blocks.

39. In a press, the combination of a press

body having top, bottom and fore and aft side walls, the top wall having a flat under face and the bottom wall having two inclined upper face portions extending downwardly and outwardly toward opposite sides of the body, a pair of tilttable wedge blocks having fulcrum portions slidably engaging the inclined face portions of the bottom wall and supporting the blocks to tilt about axes extending fore and aft of the press body, a pair of adjusting screws threaded through the side walls of the press body, a split horizontally disposed spring metal annular member interposed between the inner ends of the wedge blocks and pressing the blocks outwardly against the inner ends of the screws, a vertically movable head located under the top wall of the press body, and cam mechanism mounted on the wedge blocks for supporting and lifting the movable head.

40. In a press, the combination of a stationary upper head, a vertically movable lower head, a pair of horizontally disposed thrust plates under the lower head, a set of antifriction rollers between the lower head and upper thrust plate, a set of antifriction rollers under the lower thrust plate, a support under the lower set of rollers, a horizontal cam shaft extending between the thrust plates and adapted to shift the plates endwise in opposite directions transversely of the shaft when the shaft is rotated, means for rotating the shaft, and a pair of retainers for each set of antifriction rollers, said cam shaft being located between the inner ends of the thrust plates when the movable head is in lowered position and said retainers having projections engageable by the outer ends of the thrust plates to restore the sets of antifriction rollers to their initial positions after each operation of the press.

41. In an embossing press, the combination of fixed and movable press heads, means for shifting the movable head up and down under the fixed head, a long detachable sheet metal work carriage having a flat body portion slidably seated on the movable head and having upturned side flanges and depending end flanges, said end flanges and said movable head having registering apertures therein, a long holding and guiding rod extending through the apertures in said head and end flanges and having a head at one end engaging the outer face of one end flange and a transverse aperture near its other end just outside the other end flange of the carriage, and a removable key extending through the rod aperture and abutting against the outer face of the adjacent end flange of the carriage.

42. In an embossing press, the combination of fixed and movable press heads, means for shifting the movable head up and down under the fixed head, a long detachable

- sheet metal work carriage having a flat body portion slidably seated on the movable head and having upturned side flanges and depending end flanges, said end flanges and 5 said movable head having registering apertures therein, a long holding and guiding rod extending through the apertures in said head and end flanges and having a head at one end engaging the outer face of one end 10 flange and a transverse aperture near its other end just outside the other end flange of the carriage, a removable key extending through the rod aperture and abutting against the outer face of the adjacent end 15 flange of the carriage, and a U-shaped metal handle having reduced end portions extending through one end flange of the carriage and headed against the inner face thereof at opposite sides of the rod, the flat body portion 20 of the carriage having portions thereof stamped downwardly therefrom into vertical planes and overlying the rod adjacent each end flange of the carriage.
43. In a press, the combination of a stationary upper head, a shiftable lower head, means for guiding the lower head to shift vertically, lifting mechanism for the shiftable head disposed under and supporting said head, a base having oppositely inclined 25 faces, and adjustable supporting means for the lifting mechanism disposed between the base and said mechanism, said adjustable means including a pair of wedge blocks slidably and tiltably supported on the inclined faces of the base and provided with flat upper faces and means for independently sliding said blocks longitudinally of the inclined faces of the base and holding the same in adjusted position.
44. In a press, the combination of a stationary upper head, a shiftable lower head, means for guiding the lower head to shift vertically, lifting mechanism disposed under and supporting the lower head, a pair 40 of laterally tilttable members having flat upper faces for supporting the lifting mechanism, and adjusting mean for independently raising and lowering said tilttable members.
45. In a convertible embossing press, the combination of a stationary head member having a pressure face, means adjacent said stationary head member for detachably holding a supplemental head member against the pressure face thereof, a movable head member, means for forcing the movable head member toward the pressure face of the stationary head member, and means movable with said movable head member for holding 45 a supplemental head member thereon.
46. In a convertible embossing press, the combination of a stationary head member having a pressure face, means for detach- 50 ably holding a supplemental head member at the pressure face of the stationary head member, a movable head member, means for forcing the movable head member toward the pressure face, and a traveling support held to the movable head member therewith toward and from the stationary head member and to travel independently of the movable head member transversely of the movable head member, said support being constructed to hold a supplemental head member to travel therewith relatively to the movable head member and move with said head member toward and from the stationary head member.
47. In a convertible embossing press, the combination of fixed and movable head members, means for shifting the movable head member, a supplemental head member having a pressure face, and means for detachably holding the supplemental head member to either the fixed or movable head member with its pressure face facing the other head member.
48. In a convertible embossing press, the combination of fixed and movable head members, means for shifting the movable head member, a supplemental electrically heated head member having a heat-insulated face and an opposite heat-transmitting pressure face, means for detachably supporting said supplemental head member on the movable head member with its heat-transmitting face facing the stationary head member, and means for detachably supporting said supplemental head member against the fixed head member with its heat-transmitting face facing the movable head member.
49. In an embossing press, the combination of a two-part fixed head both parts of which have bottom pressure faces, means for removably holding the lower part of the fixed head in place, a movable head under the fixed head, means for shifting the movable head vertically, and a carriage mounted on the movable head to travel horizontally between the heads and having a continuous flat bottom.
50. In an embossing press, the combination of a vertically movable head, means for moving said head vertically, means for supporting a long flat self-heating supplemental head on said vertically movable head to travel endwise in a horizontal plane relatively to the vertically movable head and to move vertically with the latter head, and a fixed head above the vertically movable head relatively short longitudinally of the path of horizontal travel of the supplemental head.

In testimony whereof I hereunto affix my signature.

HARRISON M. SEAGERS,
